DESIGN FOR AN AUTOMOBILE HEADLIGHT LENS

Maurice A. Smith, Jeannette, Pa.

Application September 24, 1937, Serial No. 71,766

Term of patent 14 years

To all whom it may concern:

Be it known that I, Maurice A. Smith, a citizen of the United States, residing at Jeannette, in the county of Westmoreland and State of Pennsylvania, have invented a new, original, and ornamental Design for an Automobile Headlight Lens, of which the following is a specification, reference being had to the accompanying drawing, forming part thereof, in which

Figure 1 is a rear elevational view of an automobile headlight lens, showing my new design and Figure 2 a longitudinal cross-sectional view thereof taken on line 2—2 of Fig. 1.

I claim:

The ornamental design for an automobile headlight lens, as shown.

MAURICE A. SMITH.
